United States Patent Office

Des. 179,995
Patented Apr. 2, 1957

179,995

ELECTRONIC CABINET

James G. Wells, Chicago, and Herbert C. Golz, Aurora,
Ill., assignors to Elgin Metalformers Corporation, Elgin,
Ill., a corporation of Illinois

Application May 25, 1956, Serial No. 41,642

Term of patent 14 years

(Cl. D26—5)

The single figure is a perspective view of an electronic cabinet, showing our new design. The side not shown has substantially the same appearance as the side shown, and the back is conventional.

We claim:

The ornamental design for an electronic cabinet, substantially as shown and described.
